HIS ATTORNEY.

Patented July 21, 1925.

UNITED STATES PATENT OFFICE.

GEORG CANTIENY, OF BERLIN, GERMANY, ASSIGNOR TO KOHLENSCHEIDUNGS-SELLSCHAFT M. B. H., OF BERLIN, GERMANY, A CORPORATION OF GERMANY.

PROCESS OF LOW TEMPERATURE COAL DISTILLATION.

Application filed May 15, 1924. Serial No. 713,627.

To all whom it may concern:

Be it known that I, GEORG CANTIENY, a citizen of the German Republic, residing in Berlin, Germany, have invented certain new and useful Improvements in and Relating to a Process of Low Temperature Coal Distillation, of which the following is a specification.

It has become known that it is desirable 10 in connection with the treating of coal with heat, (recovery of low temperature tar, distillation at low temperatures) in retorts or like apparatus completely filled with coal, to add coke or semi-coke to the coal in order to avoid certain difficulties which otherwise are experienced therewith. This measure serves the object of facilitating the passage through the closely packed material of the heating gases and of the hydro-carbons 20 driven off during the low temperature distillation, the particles of the mass under treatment being subdivided by the additional porous material. Furthermore the additional coke, and the intermediate spaces 25 formed thereby are intended to support the transmission of the heating effect to the material, and to also effect an absorption and arrest of the residue of the volatile hydrocarbons especially of the pitch. For 30 distillation arrangements of the gas producer type, it has also been proposed to intermingle coal and coke or other suitable fuels in horizontal or vertical layers; this for the purpose of facilitating a penetration 35 of the material by the heating medium and by the gases produced and to prevent the caking together of the entire content of the apparatus to an impenetrable plastic mass.

The present invention is based upon the 40 knowledge that the addition of coke as previously proposed is capable of preventing, in other kinds of apparatus, i. e. in such in which the coal is moved along mechanically whereby it is constantly turned over and mixed, the disadvantageous caking and sticking together, which leads to a blocking of the apparatus because of a mass of conglomerated material, and to a stoppage of the operation of the installation because of 50 the sticking to the conveying means of the only partially distilled coal. This was not an obvious knowledge for the prior inventors, since the described disadvantageous properties of the caking coal did not take place, or if so to a very small extent only,

in the utilization of the half filled retorts. Not until the modern distilling devices were employed, and especially such as are fitted with a screw conveyor, agitating wings, conveying bands and rotary drums, and especially with such where the coal only partially fills an inner chamber, did the caking of the coal cause the heavy disturbances mentioned.

The process of the present invention may 65 be carried out in an apparatus such as is shown and described in my United States Patent No. 1,495,573, granted May 27, 1924, and illustrated in the sole figure of the drawing, accompanying this specification, 70 which is a longitudinal section and in which figure a furnace designated by 1 is employed for heating a revolvable retort 2 comprising an outer drum or wall 3 and an inner tubular body or tube 4 with tension or 75 spacing pieces 5 for assisting in supporting the outer drum or wall 3. There is also shown helical guiding ribs or bands 6 for facilitating the passage of the material. In other words these helical guiding ribs or 80 bands constitute mechanical conveying means for the material to be worked or under treatment.

As it is well known, the modern apparatus was designed chiefly in order to avoid, on 85 principle, the difficulties accompanying the older and completely filled retorts, which the inventors of that time thought to be able to remove by the addition of coke and the like.

According to the present invention, a certain quantity of coke or semi-coke is 90 constantly added to the material and the coal under treatment is thereby changed from a detrimental and sticky state into a crumbly and perfectly harmless condition. An ag- 95 glomeration of the material sufficient to form lumps or a sticking of the material to the conveying means or to the walls in a manner to be detrimental to the process are prevented. The material thus treated will 100 pass without difficulties through and from the conveying means.

When the process is first started the required addition may in the first instance consist of existing coke, while during the further course of the process the additional quantity may preferably be taken from the discharged final product before it is quenched. Thus in addition thereto the sensible heat contained therein is utilized again 110

for the process and furthermore the fresh material is slowly heated, which in itself causes a decrease in the tendency of the material to cake and stick.

5 The quantity of the added material will naturally depend upon the properties of the material to be treated, and the coke or solid residuals added will probably have a functional effect upon the amount of coal treated,
10 but in any event the process has the advantage of being readily adaptable to whatever material is to be or is being treated and this without it being necessary to alter the installation.

15 I claim as my invention:

1. The process for preventing the caking of bituminous materials when distilling at low temperatures in a retort, which process consists in agitating the mass of the material in the presence of coke during the distillation.

2. In the distilling of bituminous materials at low temperature in retorts fitted with mechanical conveying means for the
25 material to be distilled, the method which comprises mixing some of the solid residual

products produced by the same process with said materials and distilling said mixture while mixing the same and simultaneously therewith conveying the same through the 30 retort whereby the particles of the materials to be distilled contact with the added products substantially as described and for the purpose set forth.

3. In the distilling of bituminous materials at low temperatures in furnaces fitted with mechanical conveying means for the material to be worked, the method which consists in adding to fresh bituminous material the final solid residual product of the 40 same process while still in a hot condition and distilling the same while mixing the same and simultaneously therewith conveying the same through the furnace substantially as described and for the purpose set 45 forth.

In testimony whereof I affix my signature in presence of two witnesses.

GEORG CANTIENY.
